UNITED STATES PATENT OFFICE.

LEWIS PENGILLY, OF LOS ANGELES, CALIFORNIA.

CARRIER-OPERATED JACK AND TRUCK.

Application filed May 9, 1924, Serial No. 712,150. Renewed December 14, 1925.

This invention relates to improvements in attachments for motor vehicles, my main object being to provide a device, permanently mounted at the rear end of an automobile, by means of which the rear end may not only be raised clear of the ground, but may be moved laterally any desired distance.

Another object is to provide driving means for the device which is operated from the main drive or propeller shaft, and which is so arranged that while the device is in operation the car-wheels cannot be driven, and vice versa.

The entire operation is arranged to be controlled from the driver's seat, without any physical exertion on the part of the driver being necessary other than the manipulation of a single lever.

The main purpose of my device is to permit of easy parking of a car in limited spaces, as between two other cars parked parallel to a street-curb. At present it is necessary to spend considerable time and strength to work a car into and out of such spaces, frequently interfering with traffic on the street and possibly bumping one car or another, as is well known to those who drive cars and have had occasion to park their cars under the above recited conditions.

With my attachment, it is only necessary to drive the car in at an angle to the curb, and with the front end as close to the same as possible and in the proper longitudinal position with respect to the car ahead, and cause the attachment to be operated in such a manner that the rear end of the car will be very quickly brought to the desired location adjacent the curb, without any backward and forward maneuvering of the car, or constant turning of the front wheels, being necessary.

My device therefore fills I believe a long felt need, in providing for simpler and quicker parking, and consequent expediting the movement of traffic generally.

At the same time, the device may be used for ordinary jacking-up purposes, as when tires are to be changed and the like.

These objects I accomplish by means of such structure and relative arrangement of parts as will fully appear by a perusal of the following specification and claims.

In the drawings similar characters of reference indicate corresponding parts in the several views:

Fig. 1 is a rear end view of the attachment as applied to the rear end of an automobile.

Fig. 2 is a longitudinal section of the device, together with the driving mechanism therefor.

Fig. 3 is a fragmentary plan section of the driving mechanism on the line 3—3 of Fig. 2.

Fig. 4 is a detached section of a worm and sprocket wheel unit, showing the independent drive shafts thereof.

Referring now more particularly to the characters of reference on the drawings, the numeral 1 denotes the main supporting frame of the device, preferably forming the back plate of a housing 2 which is connected to or formed integral with the axle-housings 3 of the rear wheels 4 of the car. The housing 2 contains not only the usual differential axle-drive mechanism, but certain parts of the driving mechanism of my device, as will be seen hereinafter.

Vertically spaced lugs 5 project rearwardly from the frame or plate 1, which form bearings for screw 6, secured against vertical movement. Movable along the screw between the bearings is a block 7 having opposed pins 8 disposed in a plane longitudinally of the car and passing through horizontal slots 9 in the upper ends of arms 10. The arms are pivoted intermediate their ends on the frame 1 adjacent the lower end thereof and transversely of the screw 6. The lower ends of these arms carry small wheels or rollers 11. The above described cooperating parts are so arranged that when the block 7 is adjacent the upper end of the screw, the rollers 11 will be engaged with the ground and the wheels 4 clear of the ground a certain distance. When the block 7 is adjacent the lower end of the screw, the reverse setting of the wheels 4 and rollers 11 relative to each other obtains, as will be evident.

The screw is rotated, so as to raise and lower the roller carrying arms, by the following structure:

Mounted in connection with the screw is a worm wheel 12 engaged by a worm 13 fixed on a hollow shaft 14 projecting into and journaled in the housing 2 and having a gear 15 fixed on its inner end.

This gear is adapted to be enmeshed with a gear 16 slidably splined on the main propeller shaft 17 of the car. The gear 16 is

shifted by ordinary means, such as a fork 18 engaging a collar 19 provided with the gear, and mounted in connection with a rod 20 projecting through the front of the housing and there connected for longitudinal movement to a control lever 21 suitably located in the driver's compartment of the car.

To cause the rollers 11 to rotate so as to move the entire rear end of the car transversely when the wheels 4 are clear of the ground, I provide chains 22 passing about sprocket wheels 23 connected to the rollers and also about other sprockets 24 arranged concentric with the pivotal arcs of the arms 10. These latter sprockets are driven in common by a single chain 25 passing about a drive sprocket 26 mounted on a shaft 27 turnable in and projecting beyond the shaft 14 at both ends.

A gear 28, the same size as the gear 15, is mounted on the inner end of the shaft 27 and is adapted to be enmeshed with the gear 16 only when the latter is thrown out of mesh with the gear 15.

To prevent the propeller shaft 17 from driving the car when either shaft 14 or 27 is being driven, said propeller shaft has an extension 29 at its rear end and independent thereof, said extension carrying the usual driving bevel gear 30. The extension at its end adjacent the shaft 17 has an internal gear 31 fixed thereon, to receive the sliding gear 16 therein in driving relation, at which time the latter is clear of both gear 15 and gear 28. It will therefore be seen that with this arrangement, only one of the three driving means can be effective at one time, thereby avoiding possible accident and eliminating the necessity of any very expert handling on the part of the operator.

To reverse the shafts 14 and 27, it is only necessary to first reverse the propeller shaft 16, by means of the ordinary gear-shaft reversing means, this shaft being kept in constant rotation, preferably in "low gear" all the time the attachment is in operation. When said operation is finished, the driver throws the gear 16 into mesh with the gear 31, so as to enable the car to be then run in the usual manner.

As a safety precaution, to prevent possible breakage of the mechanism or stalling of the engine should the driver fail to disconnect the jack operating means in time, the upper and lower ends of the screw 6 are made devoid of threads to an extent sufficient to receive the block 7. Thus when the block 7 arrives at either end of the screw it is automatically disconnected from the threads, and the raising or lowering of the arms 10 at once ceases, irrespective of the continued driving of the screw.

Once the car is lifted by the jack, it may be shoved transversely by hand and without

the application of power to do so, since when the gear 28 is disconnected from the engine drive shaft, the rollers 11 will turn easily. This enables the car to be moved about in the event that the driver is absent but has left it jacked up.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A jack and truck structure for automobiles including an arm mounted thereon between the rear wheels thereof, a roller on the lower end of said arm disposed in a plane at right angles to the wheels, and normally clear of the ground, means for lowering said arm to the ground to cause the rear wheels to clear the same, said means being driven from the main drive shaft of the rear wheels, similarly driven means for rotating the roller, and means whereby the shaft will be positively disconnected from the rear wheels when the arm is being moved and the roller rotated.

2. A jack and truck structure for automobiles including an arm mounted thereon between the rear wheels thereof, a roller on the lower end of said arm disposed in a plane at right angles to the wheels, and normally clear of the ground, means for lowering said arm to the ground to cause the rear wheels to clear the same, means for then driving the roller, said means being driven from the main drive shaft of the rear wheels, similarly driven means for rotating the roller, and means whereby the shaft will be automatically disconnected from the rear wheels when the arm is being moved and the roller rotated, and the arm will be disconnected from the driving means when the roller is being rotated, and vice versa.

3. A jack and truck structure for automobiles comprising arms mounted transversely of the vehicle between the rear wheels thereof, rollers at the lower ends of the arms adapted to be engaged with the ground and disposed in a plane at right angles to the rear wheels, a shaft, means between said shaft and arms for raising and lowering the arms with the rotation of the shaft, another shaft connected in driving relation with the first named shaft, drive means for the rollers, and means for alternately placing said roller-drive means and the second named shaft into driving relation with the main drive shaft of the vehicle.

4. A jack and truck structure for automobiles comprising arms mounted transversely of the vehicle between the rear wheels thereof, rollers at the lower ends of the arms adapted to be engaged with the ground and disposed in a plane at right angles to the rear wheels, a shaft, means between said shaft and arms for raising and lowering the arms with the rotation of the shaft, another shaft connected in driving relation with the first named shaft, drive means for the rollers, and means for alternately placing said roller-drive means and the second named shaft into driving relation with the main rear-wheel drive shaft of the vehicle and for at the same time disconnecting said main shaft from the rear wheels.
5. A jack and truck structure for automobiles comprising arms mounted transversely of the vehicle between the rear wheels thereof, rollers at the lower ends of the arms adapted to be engaged with the ground and disposed in a plane at right angles to the rear wheels, a shaft, means between said shaft and arms for raising and lowering the arms with the rotation of the shaft, a second shaft connected in driving relation with the first named shaft, a third shaft connected in driving relation with the rollers, gears on said second and third shafts, a sliding gear on the main rear wheel drive-shaft of the vehicle alternately engageable with the first named gears, said drive shaft being broken between the sliding gear and the driving connection of said shaft with the wheels, and means whereby when the sliding gear is moved rearwardly beyond the first named gears the driving connection between the drive-shaft sections will be established.
6. A jack and truck structure for automobiles comprising arms mounted transversely of the vehicle between the rear wheels thereof, rollers at the lower ends of the arms adapted to be engaged with the ground and disposed in a plane at right angles to the rear wheels, a shaft, means between said shaft and arms for raising and lowering the arms with the rotation of the shaft, a second shaft connected in driving relation with the first named shaft, a third shaft connected in driving relation with the rollers, gears on said second and third shafts, and a sliding gear on the main drive shaft of the vehicle alternately engageable with the first named gears.
7. A jack and truck structure for automobiles comprising arms mounted transversely of the vehicle between the rear wheels thereof, rollers at the lower ends of the arms adapted to be engaged with the ground and disposed in a plane at right angles to the rear wheels, a shaft, means between said shaft and arms for raising and lowering the arms with the rotation of the shaft, a second shaft connected in driving relation with the first named shaft, a third shaft connected in driving relation with the rollers, gears on said second and third shafts, a sliding gear on the main rear wheel drive-shaft of the vehicle alternately engageable with the first named gears, said drive shaft being broken between the sliding gear and the driving connection of said shaft with the wheels, and an internal gear on the rear section of the drive shaft, the sliding gear engaging the internal gear when moved rearwardly of the first named gears.

In testimony whereof I affix my signature.

LEWIS PENGILLY.
